APPARATUS AND METHOD FOR PRODUCING
BUILDING BOARDS

Franz Maria Leng, Saltsjo-Duvnas, Sweden

Application January 15, 1952, Serial No. 266,558

Claims priority, application Sweden June 25, 1948

9 Claims. (Cl. 18—4)

1

The present invention relates to new and improved apparatus and method for producing building boards from wood wool, excelsior or similar vegetable fiber material in the form of elongated, elastically resilient, crooked strands, and a suitable binding agent such as Portland cement. For convenience of expression, the fiber material is herein referred generically as wood wool or excelsior.

The present application is a continuation-in-part of my copending application, Serial No. 97,178, filed June 4, 1949.

It is an object of the present invention to provide a continuous production line process for making uniform, high quality building boards from excelsior and a binding agent. The product produced in accordance with the present invention is characterized by uniformity of density and strength and by a high strength-density ratio. The bending strength about an axis transverse to the longitudinal axis of the building board is especially high. A further characteristic of the product is that the edges are straight and strong. While the density of the board is otherwise uniform throughout its area, the marginal portions become progressively denser toward the edges and the percentage of voids in the material progressively decreases so that the edges are firm and strong. The number of contacts between individual strands in the material is greater in the marginal portion, thereby providing still greater strength. At the edges, the strands are bent sharply so that one portion of a strand lies approximately in, or parallel to, one face of the board while another portion of the same strand lies approximately in, or parallel to, the edge surface of the board, for example at right angles to the first portion. The edges of the board are sharply defined and may be either square or otherwise shaped, as desired, for example to provide tongue-and-groove, shiplap or V-shaped edges.

Another object of the invention is to provide a process for making high quality building boards in a practical and economical manner. In accordance with the invention, there is a continuous flow of the material from the initial preparation of the excelsior to the finished building board. The excelsior is cut to predetermined lengths, moistened, preferably with a chemical solution, and coated with a binding agent by blowing the binder in dry powdered form into a tumbling mass of the wet fiber. The coated fiber is then strewn or scattered uniformly onto a moving train of rectangular pressing plates to deposit a layer of material on the plates and the deposited

2

material is combed to level the layer and orient individual pieces of material so as to lie approximately in the direction of movement of the plates. The material is confined on the plates so as to leave a peripheral marginal portion of each plate substantially free of material. After a preliminary compacting of the material, for example by means of rollers, the plates are stacked in superposed relationship with the layers of material therebetween. Edge-pressing strips are positioned between the marginal portions of the plates and pressure is applied to the plates and to the edge-pressing strips so as to compress the material in a direction perpendicular to the plates and also in a direction parallel to the plates. The pressing of the material, like the preparation of the material and the depositing of the material on the pressing plates, is preferably effected in a continuous manner to provide a high rate of production at low cost.

A further object of the invention is to provide compact, economical and efficient apparatus for carrying out the aforementioned process. The apparatus permits continuous operation and is, for the most part, automatic, reducing to a minimum the man-hours required in the production of the wall boards.

The objects and advantages of the invention will be more fully understood from the following description in conjunction with the accompanying drawings which show, by way of example, apparatus for carrying out the process.

In the drawings:

Fig. 1 is a schematic elevation, partly in section of a plant for carrying out the process in accordance with the invention.

Fig. 2 is a cross-section taken approximately on the line 2—2 in Fig. 1.

Figs. 3 and 4 are, together, a side elevation of the apparatus on a larger scale.

Fig. 5 is a side elevation on a still larger scale of a drum where the fiber material is coated with a binding agent, portions being broken away to show interior construction.

Figs. 6 and 7 are a bottom and end view, respectively, of the drum shown in Fig. 5.

Fig. 8 is a side elevation, partly in section, of conveyors and a picker roll for handling the fiber material.

Figs. 9, 10, 11 and 12 are, together, a side elevation on a larger scale of that portion of the apparatus that prepares and loads the pressing plates with a uniform layer of fiber material coated with a binding agent.

Figs. 13, 14, 15 and 16 constitute, together, a plan of the apparatus shown in Figs. 9 to 12.

Fig. 17 is a cross-section taken approximately on the line 17-17 in Fig. 9.

Fig. 18 is a cross-section of one form of a device for lubricating the pressing plates.

Fig. 19 is an enlarged cross-section of a dividing strip at the junction of two pressing plates.

Fig. 20 is a horizontal section taken approximately on the line 20-20 in Fig. 19.

Fig. 21 is a schematic plan on a smaller scale, showing the position of the dividing strip with respect to the pressing plates.

Figs. 22, 23 and 24 are cross-sections similar to Fig. 19 but showing alternative constructions.

Fig. 25 is an end elevation of one of the picker rolls shown in Fig. 10.

Fig. 26 is an end elevation of one of the combining or leveling rolls shown in Fig. 11.

Fig. 27 is a cross-section taken approximately on the line 27-27 in Fig. 12.

Fig. 28 is a cross-section taken approximately on the line 28-28 in Fig. 12.

Fig. 29 is an enlarged partial cross-section, showing one of the sets of rollers for guiding and supporting the pressing plates during the loading cycle.

Fig. 30 is a schematic longitudinal section illustrating the loading of the pressing plates.

Fig. 31 is a schematic cross-section showing a plurality of plates in a press with layers of material between successive plates.

Fig. 32 is a plan of the parts shown in Fig. 31 with the upper plates and upper press member removed.

Figs. 33 and 34 are a cross-section and plan, respectively, corresponding to Figs. 31 and 32 but with the parts shown in the positions they would occupy after the material has been compressed.

Fig. 35 is an end elevation showing in more detail a press for compressing the slabs of material.

Fig. 36 is a side elevation of the press shown in Fig. 35.

Fig. 37 is a plan of the press.

Fig. 38 is a schematic vertical section, showing another kind of press designed for continuous operation.

Fig. 39 is a plan of the press shown in Fig. 38.

The plant shown schematically in Figs. 1 and 2 of the drawings comprises an excelsior-preparing and treating section A where the excelsior is prepared and is coated with a binding agent, a plate-loading section B where a layer of coated excelsior is deposited on pressing plates while the latter are continuously advanced and a pressing section C where the layer of coated material is subjected to pressure to compact it in all directions.

The excelsior is produced by one or more planers 1 (Fig. 2) and cut into predetermined lengths by a cutter 2. The length of the strands of excelsior should be not less than one inch or more than six inches and, preferably, should be about three or four inches. The cut excelsior is blown through a conveyor pipe 3 into a bin 4 from where it is fed by cooperating conveyors 5 and 6 and a rotating picker roll 7 (Fig. 4) onto a sloping conveyor 8. The conveyors 6 and 8, as well as other conveyors for carrying the excelsior, preferably comprise a plurality of transversely extending plates 9 carried by spaced chains 10, each of the plates having an upwardly offset lip 11 which projects over the edge of the adjacent plates. The picker roll 7 (Fig. 8) comprises a plurality of rows of spikes 12

mounted on a suitable base or cylinder 13 and rotates in the direction of the arrow so as to strew a uniform layer of excelsior on the conveyor 8.

While traveling on the conveyor 8, the excelsior is moistened by liquid from a plurality of spray heads 15 (Figs. 1 and 4) supplied by a pump 16 from a tank 17 (Fig. 4). Excess liquid drains off through the conveyor and is collected by an apron 18 which returns it to the tank 17. A reservoir 19 supplies additional fresh liquid to the tank. If Portland cement is to be used as the binding agent, the liquid used for moistening the excelsior may be water or a weak aqueous solution. It is preferred to use a 2° to 5° Baumé solution of calcium chloride. The dry weight of the calcium chloride used should be 1½ to 3% and, preferably, about 2% of the weight of dry cement to be used as the binding agent.

A picker roll 21 discharges the material in a loose condition from the conveyor 8 into a hopper-like chute 22 which guides it into the upper end of an inclined open-ended rotating cylinder 23 (Figs. 5 to 7). The cylinder 23 is rotatably supported by spaced rollers 24 which are provided on spaced parallel shafts 25 and engage ribs or bands 26 provided on the cylinder. A roller 27 engages the lower side of one of the ribs 26 to take axial thrust resulting from the inclination of the cylinder and to keep the ribs 26 in alignment with the rollers 24. The shafts 25 are driven by chains 28 from a power shaft 29 and, in turn, drive the cylinder or drum 23 through the engagement of the rollers 24 with the ribs 26 of the drum.

A rotatable shaft 30 extends lengthwise through the open-ended drum 23 and carries a multiplicity of fingers or paddles 31 which are of such length that they come fairly close to, but do not engage, the inner surface of the drum. The shaft is eccentric of the drum and is driven in the direction indicated by the arrow in Fig. 7, for example by means of V-belts 32 (Fig. 5).

The speed of rotation of the shaft 30 is greater than that of the drum 23. For example, the shaft 30 may be rotated at 300 to 500 R. P. M. while the drum 23 is rotated at a speed of 15 to 30 R. P. M. As a result of this rotation, the wet excelsior fed into the upper end of the drum 23 is tumbled and tossed and thoroughly mixed as it travels by gravity down through the drum.

The binding agent in dry powdered form, for example Portland cement, is lifted by a conveyor 34 into a bin 35 from which it is fed by a screw conveyor 36 into the upper end of the rotating drum 23. The conveyor 36 enters the upper end of the drum 23 just above the center and to one side of the chute 22. An air blower 37 (Fig. 3) discharges a blast of air just below the discharge end of the conveyor 36 to blow the cement into the rotating drum and distribute it uniformly throughout the tumbling and tossing mass of excelsior in the drum. The cement adheres to the wet excelsior and forms a uniform coating on each strand. The wetness of the excelsior entering the drum 23 is precisely controlled to provide just enough moisture to form a cement coating on the strands of excelsior of proper consistency for maximum bonding power and strength. The addition of further water after the excelsior has been coated with cement is avoided as it would tend to wash off the cement from the excelsior.

At the lower end of the drum 23, the cement-coated excelsior is discharged onto a conveyor 38,

an adjustably swingable portion 39 comprising a plurality of parallel bars, the position of which is controlled by a handle 40, counteracts the rotational effect imparted to the material by the rotating drum 23 and assists in guiding and distributing the coated excelsior onto the conveyor. The construction of the conveyor 38 is preferably similar to that of the conveyor 6 shown in Fig. 8 and described above. The material on the conveyor 38 is further spread into a uniform layer by a pin or hedgehog roller 41 (Fig. 10) which is similar to the roller 7 (Fig. 8) and is driven so as to rotate in a clockwise direction, as viewed in Fig. 10. At the end of the conveyor 38, there are two hedgehog rolls 42 and 43 which are driven in opposite directions at relatively high speed and strew the coated excelsior into the air so that it falls in a uniform layer on pressing plates 45 (Fig. 30) which are moved under the discharging rolls 42 and 43 in a continuous end-to-end train.

The pressing plates 45 are substantially rectangular plates or slabs of suitable material, for example wood, ply-wood, pressed wood or metal, and are both longer and wider than the building boards that are to be formed. Stacks of the pressing plates 45 are brought, for example by rollers 46, to the starting end of a conveyor system 47. The pressing plates are fed one by one, either mechanically or by hand, onto a feeding table 48 having rollers 49. As the pressing plates are continually reused, they may have particles of excelsior or cement adhering to them from a previous pressing operation. To remove any such material, the plates are pressed between a pair of opposed rotation brushes 50 and 51 by means of opposed sets of spaced discs 52 and 53, at least one set being driven. The spaced discs 52 and 53 engage only small areas of the plates and thus avoid pressing adhering material into the surface of the plates. If desired, the discs may have rims or tires formed of rubber or other resilient material. The rotating brushes 50 and 51 are driven in the same direction, i. e. both clockwise, as viewed in Fig. 9. The upper brush 50 thus brushes rearwardly on the upper surface of the plate while the brush 51 brushes forwardly on the lower surface of the plate, so that the reactions of the two brushes on the plates counterbalance one another. Instead of being perpendicular to the direction of movement of the plates, as shown, the brushes 50 and 51 are desirably inclined so that any material on the upper surface of the plates is brushed toward one side edge of the plate. The cleaned plates pass between opposed rollers 54 and 55 which are preferably rubber-covered and are driven in opposite directions by a variable speed motor and reducing gear, for example by means of a chain 56 which also drives the discs 52 and 53. These rollers 54 and 55 propel a complete line of plates throughout the length of the conveyor system 47, each plate being in turn pushed by the plates to the rear of it. This simplifies the construction and operation of the conveyor system 47 and also assures continuity of the train of pressing plates presented to the excelsior-feeding apparatus.

The upper surfaces of the plates are lubricated by means of a lubricating device 57 which may be a suitable spray or, as illustrated in Fig. 18, may comprise an elongated wick 58 which extends across, and engages the upper surface of, each plate. Oil or other lubricating material in an elongated tank 59 is dripped onto the wick 58 by a plurality of spigots 60. The spigots are adjusted to provide the desired flow. As shown in

the drawing, the wick 58 comprises a plurality of felt strips which are carried by a frame supported by metal straps or brackets below the bottom of the tank 59.

In the section of the conveyor system beyond the driving rollers 54, 55, the pressing plates are continuously supported by a series of wheels or rollers 62. There is a row of wheels spaced about eighteen inches apart for supporting each edge of the plates and also a row of wheels down the middle. Additional rows may be provided, if desired, particularly for wider plates. There is also a row of wheels 63 (Fig. 29) provided above each side edge of the plate to hold it down and guard against any buckling of the train of plates. The wheels or rollers are rotatably supported by a suitable framework which is shown as being made of angle iron. The rollers are not driven but are preferably provided with anti-friction bearings so as to turn easily. The side rollers are supported by angle irons 64 that extend lengthwise of the conveyor system and guide the edges of the plates 45.

At a station shortly after the lubricating device 57, transversely extending dividing strips 65 are positioned on the pressing plates at the junctions between successive plates. A preferred form of dividing strip is shown in cross-section in Fig. 19. The dividing strips are wide enough to overlie a marginal portion of substantial width at the end of each of the adjacent pressing plates. The length of the dividing strips is less than the width of the pressing plates and the height of the strips is equal to the desired thickness of the uncompressed layer of cement-coated excelsior that is to be deposited on the pressing plates. The dividing strip is preferably trapezoidal in cross-section, being wider at the top than at the bottom, so that the forward space, and, if desired, also the rearward space, are inclined to the pressing plates (Fig. 19). Each of the dividing strips is provided with two or more anchoring blocks 66 secured to the strip by bolts 67. The anchorage blocks 66 project down through openings provided by notches in the ends of the plates. Each of the anchor blocks 66 carries an elongated button 68 rotatably supported by a shank 69 which is pressed upwardly by a spring 70 so that the button is frictionally held in whatever position it is turned. With the button 68 turned so as to be in line with the anchor blocks 66, the dividing strip is placed over the junction between two pressing plates, the anchor blocks 66 projecting through the openings formed by the notches in the rear end of the forward plates and the buttons 68 being below the lower surface of the plates. As the plates continue to move forward, propelled by the driving rollers 54 and 55, the inner ends of the buttons 68 engage cam surfaces or abutments 71 (Figs. 5, 20 and 21) to turn the buttons 68 to a position transverse to the anchor blocks 66 (Fig. 20) so that the end portions of the buttons underlie the adjacent portions of the plates to secure the dividing strips firmly in position. Reinforcing plates 72 are preferably provided on the lower surface of pressing plates 25 for engagement by the buttons 68.

In Fig. 22, there is illustrated another, and somewhat simpler, device for anchoring the dividing strips 65. This comprises a slidable latch 73 received in a hasp 74 provided on each of the anchorage blocks 66. Still other forms of the dividing strips 65 are illustrated in Figs. 23 and 24. The form shown in Fig. 23 comprises an

upper portion 75 and a lower portion 76 that are telescopically slidable relative to one another, being urged into expanded condition by springs 77. The securing means comprises opposite spring-pressed latches 78 on the anchoring blocks 79. In the form shown in Fig. 24, the dividing strip 65 comprises a casing 81 of rubber or rubber-like material which may be either hollow or filled with a compressible material such as sponge rubber. The securing means comprises opposite brake-pressed latches 82 which are similar to the latches 78 of Fig. 23 except that they have cam-shaped upper surfaces which wedge against the under surfaces of the pressing plates in order to hold the dividing strip still more firmly in place.

As the continuous train of pressing plates 45, with the dividing strips 65, moves forwardly under the spiked rolls 42 and 43 (Figs. 10 and 30), the moist cement-coated excelsior is strewn over the upper surfaces of the plates and the dividing strips, forming an approximately uniform layer. The material is confined in a lateral direction by side walls 85 which extend down to the pressing plates and closely abut the ends of the dividing strips 65 so as to keep marginal portions at the sides of the plates free of the excelsior. The side walls 85 are adjustable toward and away from one another to make different width building boards, it being understood that the dividing strips 45 would correspond in length to the various boards being made. Where wider panels are to be made, two or more sets of mixing drums and excelsior conveyors can be arranged side by side. The rotating spiked rolls 42 and 43 for strewn the coated excelsior onto the plates may be replaced by other means, such, for example, as a blower similar to the blower 37 but of larger capacity.

Following the station at which the cement-coated excelsior material is strewn onto the pressing plates, the material is acted upon by two or more successive brushes or picker rolls 87 which are rotated in a direction opposite to the direction of movement of the pressing plates and may, for example, be of the form shown in Fig. 26 with a multiplicity of rearwardly inclined fingers or spikes 88. These spiked rolls further assure uniform distribution of the material on the panels and also have a combing action that tends to orient the strands of excelsior so that they extend lengthwise of the panels. This provides greater strength in a lengthwise direction. The brushes or picker rolls 87 also reduce the height of the material on the pressing plates. The rolls 87 are adjustable vertically by means of cranks 89 and the second roll is preferably arranged somewhat lower than the first. When the material is strewn on the pressing plates, it is deposited also on top of the dividing strips which tend to produce transverse ridges of material owing to the thickness of the strips. The first roll 87 tends to level off these ridges and the second roll cleans off the tops of the dividing strips. There may, of course, be any number of rolls provided instead of only two, as shown in Fig. 15. Thus, for example, three rolls or brushes are shown in Fig. 30. The rolls or brushes may be inclined at an angle to the direction of movement of the pressing plates and successive rolls may be inclined in opposite directions to assure uniform distribution of the material.

The manner in which the cement-coated excelsior is strewn onto the pressing plates and then smoothed down is illustrated schematically

in Fig. 30. It will be seen that the material is thrown upwardly and forwardly at a comparatively high level above the pressing plates, the individual strands being thus separated and caused to fall down successively by their own weight and to be deposited on top of each other so as to form a layer of felted fibers or strands lying loosely on one another. By this felting of the fibers, greater homogeneity and strength are imparted to the finished board. Moreover, the combing action of the brushes or spiked rolls 87 orients a substantial portion of the strands or fibers, for example thirty to sixty percent, so that they lie in a direction approximately longitudinal of the finished board. This orientation of the fibers result in still greater bending strength in a lengthwise direction. The thickness of the layer of material on the pressing plates, as determined by the height of the dividing strips and the vertical adjustment of the levelling rolls 87, is chosen so as to give the desired density of the finished board after it has been compressed to a predetermined thickness. For example, the layer in its unpressed condition may be three to six times greater than the desired thickness of the finished board.

As the pressing plates move forwardly, the side edges of the material deposited on the plates is confined, for example by side strips 90 (Fig. 27) which, like the side walls 85, are adjustable for wider or narrower boards.

Following the levelling rolls 87, the layer of material on the plates 45 is subjected to a preliminary pressing between a supporting roller 92 which is underneath of, and supports, the plate and a pressing roller 93 which engages the upper surface of the material. The roll 93 is adjustable vertically and is preferably provided with a scraper or doctor blade to keep its surface clean. The opposite side edges of the layer of material are also pressed by opposite frusto-conical rollers 94 which produce even edges that slope inwardly and upwardly so that the material lying on the pressing plates is in the form of a frusto-pyramid. The side rollers 94 are adjustable toward and away from one another for different widths. All of the rollers, 92, 93 and 94, are driven through a reducing gear and sprocket chain 95 by a motor 96 which is preferably a variable speed motor. While the step of preliminary pressing can, if desired, be omitted, it is preferable in that it reduces the height of the material and thereby reduces the height of a stack of the plates when they are subsequently put in a press for final pressing. The preliminary pressing also decreases the mobility of the material on the plates so that the plates can be handled more easily without danger of the material shifting. The side rollers 94 also regulate, and preferably reduce, the width of the material. By compacting the material the edges in advance of the upper and lower rollers, they provide somewhat greater density of material along the lateral edges and hence cooperate with the subsequent edge pressing in providing strong edges of greater density in the finished board.

The rollers 92 and 93 are driven in the direction of movement of the pressing plates at such speed as to move the plates more rapidly than they are moved by the original driving rolls 54 and 55. This effects a separation of successive panels. At the same time, the buttons 98 (Figs. 19 to 21) that hold the dividing strips 65 engage cam surfaces or abutments 99 which are located ahead of the preliminary pressing rollers 93, 94,

and turn the buttons to a position in which they are parallel with the anchoring blocks 66. The dividing strip 65 is thereby released and as the pressing plate continues to move forwardly, the dividing strip is pushed off of the end of the pressing plate by the abutments 93. The dividing strips drop down onto a conveyor belt 109 (Figs. 9 to 12) which carry them back to the station at which they are positioned on the pressing plates, as described above.

With the form of dividing strips shown in Fig. 22, the strip is released by engagement of the head portion of the latch pin 73 with a stationary abutment 99 placed ahead of the preliminary pressing rollers. The forms of dividing strips shown in Figs. 23 and 24 are released automatically by the separation of successive pressing plates resulting from successive plates being seated up by the rollers 92 and 93 (Fig. 12). Alternatively, the dividing strips shown in Figs. 23 and 24 may be left in position during the preliminary pressing since these strips are compressible. Moreover, it will be seen that these strips are larger at the top and that compression of the strips in a vertical direction will result in the application of a compressive force tending to compress the end edge of the layer of material on the pressing plates. This cooperates with the final pressing operation described below, to provide firm, strong end edges of the finished board. Following the preliminary pressing, the pressing plates are delivered onto a conveyor consisting of freely turning rollers 102 by which the plates are transported to the pressing station where they are stacked on top of one another, either by hand or mechanically, for the final pressing operation.

The pressing operation is illustrated schematically in Figs. 31 to 34. A plurality of pressing plates 45, each with a uniform layer of cement-coated excelsior M, are superposed on one another in a press P having a bottom 105, a top pressing member 106, opposite side pressing members 107 and opposite end pressing members 108. An additional pressing plate 45 is preferably placed on top of the uppermost layer of material M. As described above, the marginal portions of the pressing plates, both at the sides and at the ends, are kept free of the layer of material. Side edge-pressing strips 110 and end edge-pressing strips 111 are interposed in the free spaces between the marginal portions of the pressing plates, as shown in Figs. 31 and 32. Preferably, the edge-pressing strips 110 and 111 are positioned between successive plates as the latter are stacked, either before or after they are put in the press. The edge-pressing strips 110, 111 are of the thickness desired for the finished building boards and are sufficiently wide that they project beyond the edges of the pressing plates. Preferably, a small space, for example half an inch, is left between the inner edges of the edge-pressing strip and the edges of the material M. There is also a space between the side strip 110 and the ends of the end strip 111 so that the side strips can be moved inwardly, as described below. Alternatively, the ends of the edge-pressing strips 110, 111 may be mitred like a picture frame, space being left between the mitred ends so that all of the strips can be pressed inwardly. It will be understood that the number of pressing plates 45 in the stack will ordinarily be much greater than is shown schematically in Fig. 31.

After the stack of pressing plates has been thus

prepared, it is compressed in a vertical direction by the exertion of pressure on the topmost pressing plate by the upper press member 106. This pressure is such that the pressing plates are caused to bear against the edge-pressing strips 110, 111 which thus serve accurately to limit the compression of the material M. The space between the edges of the layer of material and the edge-pressing strips and the fact that the edge-pressing strips are unconfined prevent the material from being squeezed out into the space between the upper surfaces of the edge-pressing strips and the lower faces of the pressing plates above them. It will be understood that, because of the felted condition of the strands, as described above, the material does not flow like ordinary concrete. The above-described preliminary pressing also assists in providing well defined edges.

10 The edge-pressing strips 110, 111 are then subjected to pressure in the directions indicated by the arrows (Figs. 31 and 32) to press them into the positions shown in Fig. 33. The edge strips are preferably all moved in simultaneously although, if desired, they may be moved in opposite pairs. After the pressing plates 45 have been pressed down into engagement with the edge-pressing strips 110, 111, the pressure of the upper press member 106 may be slackened off sufficiently to permit the edge-pressing strips 110, 111 to be moved in without difficulty. The width of the edge-pressing strips and the length of the end strips 111 are preferably such that, when the edge strips are pressed inwardly to the position shown in Figs. 33 and 34 with their outer edges flush with the edges of the pressing plates and with the side edge-pressing strips 110 in engagement with the ends of the end pressing strips 111, the material M is compressed to the exact size of board desired. The dimensions of the board can thus be very accurately predetermined. After the edge-pressing strips have been pressed in, the vertical pressure of the pressing member 106 is increased so that the edge-pressing strips are clamped fast between the pressing plates 45. The material is then left to solidify, either in the press or, alternatively, clamps may be applied to the stack of plates so that they can be removed from the press without material loss of pressure. After the material has attained the requisite rigidity through the hardening of the cement or other binding agent, the pressure is relieved, whereupon the edge-pressing strips and the pressing plates are removed for re-use.

20 The edge-pressing strips 110, 111 may be guided in any suitable manner so that they will perform rectilinear parallel movements. They may, for example, be guided by means of guides provided in the upper sides of the pressing plates 45 or by the press in which compression of the material is effected.

25 By suitably forming the inner borders of the edge-pressing strips, any desired edge profile can be obtained in the finished board. It is thus possible to provide boards with a tongue or bead extending along one or more edges and projecting from the edge surface of the boards by providing the inner edges of the edge-pressing strips 110, 111 with correspondingly shaped grooves. In a similar manner, the finished board may be provided with grooves extending along one or more edges of the board by providing the edges of the edge-pressing strips 110, 111 with projecting tongues. It is thus possible to manufacture

30 35 40 45 50 55 60 65 70 75

boards with tongues and grooves or other edge

configuration to provide for tight joints between adjacent boards.

A suitable press for carrying out the final pressing step of the process in accordance with the invention is illustrated in Figs. 35, 36 and 37 which are, respectively, an end elevation, side elevation and plan with certain parts broken away and shown in section. The press P comprises an open structural steel framework comprising side members 115, top members 116 and bottom members 117. At each end of the press, there is an open-work structural steel gate 118 which, at one side, is hinged to the side of the press, at 119, and, at the other side, is provided with means for securing the gates in closed position, such means being shown in the form of bolts or pins 120 insertable into aligned apertures in portions of the gate and the side structure of the press, respectively. The bottom of the press is provided with a plurality of transverse supporting rails 122 and a plurality of transverse rollers 123 parallel to, and between, the rails. The rollers 123 can be raised and lowered, for example by means of hydraulic cylinders and pistons 124. In loading the press, the rollers 123 are raised so that a stack of pressing plates can be readily rolled into the press and are then lowered so that the plates rest on the rail 122. An upper pressing member 126 is carried by the top frame structure 116 of the press and actuated by a hydraulic cylinder 127 to apply pressure to the top of the stack of plates. At opposite sides of the press, there are provided side pressing members 128 which are carried by the side structures 115 and actuated by hydraulic cylinders 129 to apply pressure to the side edge-pressing strips 110 (Fig. 32). On the opposite end gates 118 of the press, there are mounted end-pressing members 130 actuated by hydraulic cylinders 131 to apply pressure to the end edge-pressing strips 111. The hydraulic cylinders are centrally, and preferably automatically, controlled to provide the sequence of pressing steps described above. Thus, for example, fluid pressure is applied to the cylinder 127 to move the upper pressing member 126 downwardly until the pressing plates are pressed into engagement with the edge-pressing strips. The pressure in cylinder 127 is then partially relieved and fluid pressure is supplied simultaneously to the hydraulic cylinders 129 and 131 to press all of the edge-pressing strips 110, 111 in simultaneously. The pressure in hydraulic cylinder 127 is thereupon increased to clamp the edge-pressing strips firmly between the pressing plates 45.

Figs. 38 and 39 illustrate a method of continuous manufacture of the boards wherein the compression of the material is effected solely by the weight of the pressing plates and the layers of material piled on top of each other. The plates, together with the layers of coated excelsior material, are stacked on one another, as described above, but in greater number and under such conditions that effective compression of the material is obtained solely by the weight of the parts comprised in the pile.

To facilitate stacking the plates in high piles, the method utilizes a vertical shaft 135 which may be built, for example, of concrete and which has a vertical shaft opening with a cross-sectional area for the greater portion of its height corresponding to the size and shape of the pressing plates 45. However, the upper portion of the shaft flares outwardly on all four sides so that the opening at the top has a cross-sectional area

corresponding to that occupied by the pressing plates and the side and end edge-pressing members before the latter have been pressed inwardly. The upper end of the shaft 135 preferably terminates at, or slightly above, the floor 136 on which the plate-loading portion of the apparatus is located so that the pressing plates may be brought directly to the upper end of the shaft 135 by the conveying mechanism provided. At opposite sides of the shaft 135, there are provided vertically movable supporting members for successively lowering a pile of pressing plates, each with a layer of material stacked in the shaft. In the example shown, the supporting members consist of projections or lugs 137 on endless chains 138 running over wheels or pulleys 139. The feeding of the chains may be controlled manually from the working station at the top of the shaft or it may be effected continuously. The upper portions of the chains extend in an inclined position in such manner that the lugs 137 are caused automatically to engage the edges of the pressing plates. At the location of the lugs 137, the edge-pressing members are preferably recessed to permit the lugs to come in between successive pressing plates.

The pressing plates 45, each with a layer of material deposited as described above, are stacked on top of one another in the shaft 135. After a suitable number of plates have been piled on top of each other in this manner, a thicker plate 140 is laid on top of the last pressing plate, whereupon another pile section is built up resting on the plate 140. Preferably the plate 140 is metallic and of sufficient weight to cause the filling material to become compressed completely or in a considerable degree in the upper portions of the pile. The plate 140 is smaller than the pressing plates 45 so that there is a free space at opposite sides of the pile into which the lugs 137 may project. The spacing between successive lugs 137 on the chains 138 is equal to the distance between successive plates 140.

As successive sections of the pile between the plates 140 move downwardly, the cement-coated excelsior material on the plates is first compressed in all directions. Compression in a vertical direction is effected by the weight of superposed plates while compression in a direction parallel to the plane of the plates is effected by the edge-pressing strips being pressed inwardly by the inclined walls of the tapered portion of the shaft. If desired, the tapered portion of the shaft may be lower down, instead of at the top of the shaft, so that more vertical compression is effected before the edge-pressing strips are pressed in. After compression of the material in all directions has been effected, this compression is maintained as the plates continue to move downwardly in the shaft. The depth of the shaft is such that the binding agent will have hardened sufficiently by the time the plates reach the bottom of the shaft.

When the lowest pile section reaches its lowermost position, the same is delivered onto a rolling table 142 which is somewhat resilient in a vertical direction so that the section will be separated from the section next above. The lower pile section may then be conveyed out of the shaft in a horizontal direction through an opening in the shaft wall, the plate 140 remaining on the topmost pressing plate so as to maintain pressure. As further pressing plates are stacked up in the upper portion of the shaft, the pile is lowered in the manner described above by means of the chains 138 which are operated in unison to keep the

plates level. The chains 138 are preferably arranged in individual inwardly opening channels 143 provided in the side of the shaft 137. Instead of discharging a pile of pressing plates at a time, the plates may be discharged individually or in smaller groups at the bottom of the shaft, suitable escapement mechanism being provided for releasing one or more pressing plates at a time while holding the remaining plates that are stacked in the shaft.

By making the shaft sufficiently high, the pressing operation may proceed continuously since the time required to permit the material to pass through the shaft will be sufficient to permit the binding agent to harden to such extent that the boards will maintain their shape when removed from the shaft.

The process and apparatus in accordance with the invention thus make it possible to produce in a continuous, efficient and economical manner, building boards and panels of high quality having the desirable characteristics described above. It will be understood that the apparatus shown in the drawings is solely by way of example and that the invention is not limited to the details of construction shown and described.

What I claim and desire to secure by Letters Patent is:

1. A continuous process for forming boards from wood wool material and cement, which comprises wetting said material, tumbling the wet material, blowing dry powdered cement into the tumbling mass of wet material whereby the cement adheres to the wet material and forms a coating thereon, scattering said coated material, while still wet but without the addition of water after coating, onto a moving train of rectangular plates separated by transverse dividing strips which overlie the end portions of the plates and project up above the upper surface of said plates, to deposit a layer of material on said plates and dividing strips, combing the deposited material in a direction opposite to the direction of movement of the plates to level the material on said plates to the level of the tops of said dividing strips and to remove the material from the tops of said strips, confining the side edges of the material to keep the marginal side edge portions of the plates free of the material, separating said plates, removing said dividing strips, stacking a plurality of said plates in superposed relationship with the layers of said material therebetween, placing a top plate on the uppermost layer, positioning end edge strips between the end edge portions of successive plates in the spaces formerly occupied by the dividing strips, positioning side edge strips between the side edge portions of the plates kept free of said material, and applying pressure to the uppermost and lowermost plates and to opposite ones of said edge strips to compress said material in a direction perpendicular to the plates and also in a direction parallel to said plates.

2. A method of manufacturing building boards from wood wool material and a binding agent, which comprises forming a uniform layer of a mixture of the material and the binding agent on the central area only of a plate, marginal portions of the plate being left free of said mixture, stacking a plurality of plates with layers of said mixture thereon on top of one another with intervening marginal frame members between successive plates successively compressing said layers of said mixture in a lateral direction by displacement of said frame members toward one

another, and concurrently subjecting said layers to a successively increasing vertical pressure through the weight of the upper portions of the stack of plates, and successively removing from the lower portion of said stack boards formed by the compression of said layers together with the respective plates, the stack being successively lowered as boards are removed.

3. Apparatus for forming boards from wood wool material and a binder, comprising a plurality of pressing plates, means for spreading a uniform layer of a mixture of said material and binder successively on said plates, a plurality of said plates being stacked on one another with said layers therebetween, frame members arranged in opposite pairs between the marginal portions of said plates, vertically extending endless conveyors disposed at opposite sides of said stack and provided with supporting members engaging selected plates in said stack, said conveyors being operable successively to lower said plates, means for successively moving opposite ones of said frame members toward one another to compress marginal portions of said layers in a direction parallel to the plates and means for removing from the bottom of said stack boards formed by the compression of said layers together with the respective pressing plates.

4. A continuous process for forming boards from wood wool material and cement, which comprises wetting said wood wool, blowing dry powdered cement into the tumbling mass of wet wood wool whereby the cement adheres to the wet wood wool and forms a coating therein, scattering said coated wood wool while still wet but without the addition of water after coating into a moving train of rectangular pressing plates to deposit a layer of said material on said plates, the coated wood wool being whirled up in a spreading chamber located above said plates and allowed to fall down on said plates to form a layer of felted small particles, the spreading of the layer in a transverse direction being limited by side walls of said chamber extending upwardly from said plates to provide marginal portions of said plate free from said material, combing the deposited material to level the same, separating said plates and stacking a plurality of said plates in superposed relationship with the layers of said material therebetween, positioning edge-pressing strips between the marginal portions of said plates, and applying pressure to said plates and to said strips to compress said material in a direction perpendicular to the plates and also in a direction parallel to said plates.

5. In apparatus for forming boards from wood wool material and a binding agent, a plurality of pressing plates, a conveyor track, means for moving said plates along said track in edge-to-edge relation, a chamber provided above said track, said plates successively forming a bottom wall for said chamber as they are moved along said track, means for mixing the wood wool with the binder, means for feeding the freshly mixed material into said chamber and strewing it evenly over central areas of successive plates as they are moved under the chamber, means for equalizing the layer over said central areas, means for keeping said mixture off marginal portions of said plates, pressing means for receiving a plurality of said plates stacked one above another with said layers therebetween, pairs of edge-pressing strips inserted between opposite marginal portions of successive plates, means

for pressing said plates toward one another to compress the material between them and means for pressing opposite edge strips toward each other to compress marginal portions of said layers in a direction parallel to the planes of said plates.

6. Apparatus according to claim 5, in which the lower edges of side walls of the spreading chamber are adjacent to the upper surface of the pressing plates so as to limit the spreading of the layer of the material in a lateral direction.

7. Apparatus according to claim 5, in which removable separating strips projecting upwardly above the plane of the plates are so arranged along the transversely extending edges of adjacent plates as to limit the spreading of the layer of the material in a longitudinal direction.

8. In apparatus for forming boards from wood wool material and cement, means for wetting and tumbling said material, means for blowing dry cement into the tumbling mass of wet material to coat said material with cement, a plurality of pressing plates, a conveyor track, means for moving said plates along said track in edge to edge relation, separating strips extending 25 transversely of said track and projecting upwardly from the adjacent edges of successive plates, a chamber provided above said track in such position that said plates successively form a bottom for said chamber as they are moved along said track, said chamber being narrower than the plates in a direction transverse of the track so that marginal portions of said plates project beyond said chamber, means for strewing the freshly coated material in said chamber 30 35

so that it falls onto said plates as they are moved under said chamber, means for equalizing the layer of material thus strewed onto the plates and for removing said material from the tops of said separating strips, means for preliminarily pressing the material on said plates, means for separating successive plates from one another and removing the separating strip from between them and means for subjecting said material to further pressure while still on the plates on which it was originally strewed, said further pressure being exerted in a direction perpendicular to the plate and also against the edge portions of said material in a direction parallel to said plate.

9. A process according to claim 4 in which the spreading of said layer of material in the direction of movement of the plates is limited by removable separating strips covering adjacent edge portions of the successive pressing plates.
